CLAIM

The ornamental design for a nesting dish drying rack, as shown and described.

DESCRIPTION

FIG. 1 is an upper-front-right perspective view of a nesting, dish drying rack in a first configuration according to the present invention, the upper-front-left view being significantly reciprocal of the upper-front-right view, wherein the first configuration is one where a movable divider is raised; FIG. 2 is another upper-front-right perspective view of the nesting, dish drying rack of FIG. 1 in a second configuration, the upper-front-left view being significantly reciprocal of this upper-front-right view, wherein the second configuration is one where the movable divider is lowered; FIG. 3 is an upper-back-right view of the nesting, dish drying rack of FIG. 1 in the first configuration, the upper-back-left view being significantly reciprocal of the upper-back-right view; FIG. 4 is a further upper-front-right perspective view of the nesting, dish drying rack of FIG. 1 in the second configuration, the upper-front-left view being significantly reciprocal of this upper-front-right view; FIG. 5 is a bottom-back-left view of the nesting, dish drying rack of FIG. 1, the bottom-back-right view being significantly reciprocal of the bottom-back-left view; FIG. 6 is a left view of the nesting, dish drying rack of FIG. 1 in the first configuration, the right view being significantly reciprocal of the left view; FIG. 7 is a front view of the nesting, dish drying rack of FIG. 1; FIG. 8 is an upper view of the nesting, dish drying rack of FIG. 1 in the first configuration; FIG. 9 is an upper-front-left view of two of the nesting, dish drying racks of FIG. 1 in the second configuration, the upper-front-right view being significantly reciprocal of this upper-front-left view, wherein the two nesting, dish drying racks are nested; and, FIG. 10 is an upper-front-right view of the two nesting, dish drying racks of FIG. 1 in the second configuration and nested as in FIG. 9, the upper-front-left view being significantly reciprocal of this upper-front-right view.
